CLAIM

The ornamental design for a suture button, as shown and described.

DESCRIPTION

FIG. 1 is a front, top, and side perspective view of my suture button;

FIG. 2 is a front elevation view thereof;

FIG. 3 is a rear elevation view thereof;

FIG. 4 is a right side view thereof;

FIG. 5 is a left side view thereof;

FIG. 6 is top view thereof; and,

FIG. 7 is a bottom view thereof.

The portions of the suture button shown in dotted lines do not constitute a part of the claimed design.
